UNITED STATES PATENT OFFICE.

CHARLES A. FORD, OF NEWARK, NEW JERSEY.

DESIGN FOR A THUMB-TACK.

45,384.

Specification for Design.

Patented Mar. 3, 1914.

Application filed July 21, 1913. Serial No. 780,403. Term of patent 7 years.

To all whom it may concern:

Be it known that I, CHARLES A. FORD, a citizen of the United States, residing at Newark, in the county of Essex and State of New Jersey, have invented a new, original, and ornamental Design for Thumb-Tacks, illustrated in the accompanying drawing, in which—

Figure 1 is a front elevation of the thumb tack, and Fig. 2 is a side elevation thereof.

I claim:

The ornamental design for thumb tack, as shown.

CHARLES A. FORD.

Witnesses:

HENRY BOSSET,
GEORGE REBSCH.
